MACHINE KNITTING

Reference is made to my pending patent application, Ser. No. 694,655 filed 29 Dec. 1967, for disclosure of a basic method for warp-knitting bifurcated tubular fabric articles in seamless form. A Raschel machine suited to practicing that method, and for doing so to make the fabric disclosed in the present application, is known in the trade as the "Fashion Master" machine, is available commercially from Cocker Machine & Foundry Company, Gastonia, North Carolina, and is disclosed in its essentials in my pending patent application, Ser. No. 759,587 filed 13 Sept. 1968, filed jointly with Walter L. Diehl and assigned to that company.

A primary object of the present invention is provision of an attractive filigree-like warp-knit structure.

Another object is incorporation of such structure in seamless bifurcated tubular fabric articles useful as panty hose and the like.

A further object is Raschel knitting thereof.

Other objects of this invention, together with means and methods for attaining the various objects, will be apparent from the following description and the accompanying diagrams.

FIG. 1 is a flat view of a band of bifurcated tubular fabric warp-knit according to this invention;

FIG. 1a is an enlarged detail view of a single-thickness portion of FIG. 1 in stylized form rather than photographic representation;

FIG. 2 is a schematic threading diagram for the yarn guide bars of a Raschel machine patterned to make the tubular fabric of the preceding views;

FIG. 3 is a point pattern or schematic stitch diagram for the respective guide bars thereof; and

FIG. 4 is a fragmentary fabric point pattern or schematic stitch diagram of the construction at the outer edges of the band and along the center line of the unitary or wide portion and the inner edges of the bifurcated or narrow portions.

In general, the objects of the present invention are accomplished by warp-knitting seamless tubular fabric having a filigree-like net construction wherein each threaded yarn guide for the basic net is patterned to stitch consecutively on each of three adjacent needles so that the intermediate needle receives a stitch following each stitch on either of the flanking needles. The net is formed by two guide bars per bed, each threaded two in, one out, four in, one out over substantially their entire length but out of phase as to the number in. Two connector guide bars, one for each bed, each threaded at one guide only, duplicate the action of the bars for the basic net at each edge of the band, except that one of the flanking needles is outside the band, and instead of stitching on that needle the guide crosses over and stitches on the edge needle in the other bed.

FIG. 1 shows a band of fabric as produced according to this invention. The band comprises a succession of unitary wide tubular portions alternating with pairs of side-by-side narrow tubular portions (sometimes called bifurcated portions herein) and joined end-to-end thereto. The various parts into which the band is divided or proposed to be divided are referred to by appropriate letters (B for the body or wide portions, and L for the leg or narrow portions) and by successive numbers (1, 2, etc.; and also by 1', 2', etc. for the leg portions). The interchange locations between body and leg portions are designated by transverse broken lines thereacross and referred to by the letter I followed by the number designating those portions (e.g., I-1, I-2, etc.). Transverse locations along which the band is to be severed into individual

fabric articles are designated by broken lines extending beyond the edges of the band and are referred to by the letter C followed by the numbers of the respective portions to be cut apart (e.g., C-12, C-23, etc.).

FIG. 1a shows an artist's stylization of a fragment of the fabric band (one thickness only) of FIG. 1 to convey an impression of the filigree-like appearance of the fabric without attempting to depict photographically what is too intricate to follow readily with the eye. Visualization of the intricacies of 10 the actual structure will be aided by consideration of the subsequent views, and the accompanying tables.

The fabric articles of this invention are knit conveniently on a Raschel machine having at least a dozen yarn guide bars: two for the basic net on the front needlebed, two for the basic net 15 on the back needlebed, two for connecting the rightmost edge, two for connecting the leftmost edge, and four intermediate bars (two each for each of the two inner edges of the bifurcated portions). The description will be based upon a fourteen-bar machine (such as the aforementioned "Fashion Master") with bars 5 and 10 not threaded, i.e., "out." The reference numerals for the guide bars are underlined or italicized to distinguish them readily from the low-numbered needle numerals. The needles are numbered from right to left, as is conventional. Intermediate guide bars 6, 7, 8, and 9 are actuated or "shogged" by pattern chains (two alternative chains per bar) on a drum at the left side of the machine, and the rest of the guide bars are controlled from the usual drum and pattern chains at the right end of the machine. The pattern chain link numerals (0, 2, 4, etc.) for the respective guide bars are referred to the drum end of the machine.

The following table lists the starting points (front needlebar up) for the threaded guide bars.

TABLE I

35

Chain Drum	Guide Bar	Pattern Link	Between Needles
40	Right <u>1</u>	2/0	1,2
	Right <u>2</u>	6/4	3,4
	Right <u>3</u>	4/2	2,3
	Right <u>4</u>	2/0	191,192
	<u>5</u>	bar out	
45	Left <u>6</u>	0/2	98,99
	Left <u>7</u>	4/6	95,96
	Left <u>8</u>	2/2	97,98
	Left <u>9</u>	4/4	95,96
	<u>10</u>	bar out	
50	Right <u>11</u>	2/2	1,2
	Right <u>12</u>	2/2	191,192
	Right <u>13</u>	2/2	1,2
	Right <u>14</u>	4/4	2,3

FIG. 2 is the corresponding threading diagram. Guide bar 1 on the front bed and bar 13 on the back bed are threaded alike, as are bars 2 and 14 on the respective beds. All four of those bars, which form the basic net of the fabric, are threaded two in, one out, four in, one out (but remaining out of phase as to the number in) over the portion of the bed length omitted from the view in the interest of simplification. The indicated band width is 192 needles.

The next table gives the chain readings for the respective guide bars. The intermediate bars have two patterns each, designated by the bar number followed by A and B, respectively, to denote the respective bifurcated (or leg) and unitary (or body) patterns.

TABLE II

Guide Bar No.	Right drum				Left (double chain) drum								Right drum			
	1	2	3	4	6A	6B	7A	7B	8A	8B	9A	9B	11	12	13	14
Needlebed:																
F-----	2/0	6/4	4/2	2/0	0/2	0/2	4/6	4/6	2/2	2/2	4/4	4/4	2/2	2/2	2/2	4/4
B-----	2/2	4/4	2/2	2/2	2/2	2/2	4/4	4/4	0/2	0/2	4/6	4/6	2/0	2/0	6/4	
F-----	2/4	2/4	0/2	2/4	4/2	2/4	4/2	4/2	2/2	2/2	4/4	4/4	2/2	2/2	2/2	4/4
B-----	4/4	2/2	2/2	4/4	2/2	4/4	2/2	4/2	4/2	4/2	4/2	4/2	0/2	2/4	2/4	2/4
F-----	6/4	2/0	2/2	4/4	2/2	4/6	2/2	0/2	2/4	4/4	2/4	2/2	2/0	4/2	4/4	2/2
B-----	4/4	2/2	2/0	4/2	2/4	4/4	2/4	2/2	4/6	4/6	4/4	0/0	2/2	6/4	2/0	

TABLE II

Guide Bar No.	Right drum				Left (double chain) drum									Right drum			
	1	2	3	4	6A	6B	7A	7B	8A	8B	9A	9B	11	12	13	14	
Needlebed:																	
F-----	2/4	2/4	0/2	2/4	4/2	4/2	4/2	4/2	4/4	4/4	4/4	4/4	2/2	0/0	2/2	4/4	2/2
B-----	2/2	4/4	2/2	2/2	2/2	2/2	2/2	2/2	4/2	4/2	4/2	4/2	0/2	2/4	2/4	2/4	2/4

FIG. 3 shows the resulting stitch patterns schematically in point pattern form. From that view it is apparent that guide bars 1 and 2 on the front bed zigzag laterally exactly out of phase with one another to both right and left of an intermediate needle position, stitching successively at each position so that each intermediate needle of the three upon which each bar stitches receives a stitch following each stitch on either of the needles flanking it. Bars 13 and 14 stitch likewise on the back bed. In this way a panel of fabric having the basic net is formed on the front bed, and a like fabric panel is formed opposite and parallel to it on the back bed. In the unitary or body portion the singly threaded intermediate bars substitute for an unthreaded central position on those basic bars and stitch likewise. Thus, 6B is like 2, 7B like 1, 8B like 14, and 9B like 13.

The remaining guide bars function to connect the outer edges (3 and 11 at the right, 2 and 12 at the left) of the two fabric panels into tubular form. These connector bars are patterned singly threaded at edge positions where the basic bars are unthreaded so that the resulting structure is identical with that in the panels proper, thereby rendering the construction truly seamless. Each such bar is patterned like the corresponding bar forming the basic net except that the "intermediate" needle is located at the edge of the band so that stitching can shift to one flanking needle position only, whereupon after stitching on the "intermediate" (i.e., edge) needle the guide crosses over and stitches on the corresponding edge needle of the other bed before returning to stitch on the first bed.

When intermediate bars 6, 7, 8, and 9 are in their A pattern, they interconnect the fabric panels along the respective inner edges (7 and 9 at the right, 6 and 8 at the left) of the narrow tubular portions where the fabric is bifurcated.

FIG. 4 shows schematically the fabric stitch pattern along the outermost edges and the inner edges or center panel portion. The bars forming the basic net are shown in single lines, solid on the front bed and broken on the back bed, and the top row of bar numerals immediately below the stitch diagram identifies representative yarn ends guided by each of such guide bars. The stitches made by the connector guide bars are shown in double lines shaded variously to aid in following them visually from course to course, and their reference numerals appear in the lowest row. The numerals above the stitch diagram denote the needles, and it will be understood that the diagram is broken away at the missing needle numerals, as well as fragmentary along the needle positions adjoining the portions broken away. In this view the crossing over of the connector bars from one needlebed to the other is readily seen, as is the duplication of the basic net pattern by the intermediate bars in the unitary or B portion shown extended centrally toward the top of the view, where the pattern along the outer edges remains the same as in the lower or A pattern portion, where it is set forth.

It will be understood that, in Table II and FIGS. 3 and 4, only a single repeat, constituting four courses, of each different pattern is shown. Each such pattern portion for the intermediate bars usually is repeated dozens or hundreds of

times before interchanging to the other pattern, at least in the instance of intended panty hose use. The type or types of yarn will depend in large part upon the intended use, and this invention is not limited to any particular yarn composition, count, or denier. The 192-needle setout is merely by way of example.

The filigree-like appearance of this fabric is especially attractive in garment fabrics. Its construction has a desirable elasticity and is adapted to fitting a wide range of sizes while maintaining its characteristic appearance. Manufacture thereof according to this invention is quite simple and reliable, as well as economical.

The invention itself is defined in the following claims.

What is claimed is:

1. In double needlebed warp-knitting, wherein a pair of panels of fabric of equal band width are knitted opposite and parallel to one another and their opposing lateral edges are knitted together simultaneously to form seamless tubular fabric, the improvement comprising forming a basic filigree-like net construction thereof with four basic yarn guide bars, being two bars per bed, each bar having its yarn guides threaded two-in, one-out, four-in, one-out over substantially the entire panel width and out of phase with one another; patterning each basic bar to stitch with a four-course repeat, yarn from each threaded guide stitching in successive courses on a given needle, then on an immediately adjacent needle to one side of the given needle, then back on the given needle, then on an immediately adjacent needle to the other side of the given needle, and repeating; interconnecting the edges with four outer connector yarn guide bars, being two bars per bed, one bar at each fabric panel edge, each connector bar having only a single guide threaded; and patterning the respective outer connector bars to stitch in like manner to the basic bars but interchanging from bed to bed upon reaching the edges of the band and thereby connecting the fabric panels along their edges into seamless tubing.

2. Warp-knitting according to claim 1 to form a furcate fabric article comprising a plurality of side-by-side partial-width tubes for part of the article length and bordering an intervening locus of furcation, and forming unitary partial-width tubes for the rest of the article length; including knitting with four intermediate connector yarn guide bars, two per bed, each having only one guide threaded, along each such locus of furcation in place of threaded guides of the respective basic bars thereat, patterning the intermediate connector bars like the outer connector bars to interconnect intermediate edges of the respective side-by-side tubes throughout the furcate part, and patterning the intermediate bars like the basic bars for the unitary tubing throughout the rest of the length of the tubular fabric to form the basic net construction.

3. Warp-knitting bifurcated tubular fabric according to claim 2, utilizing chain readings for the respective yarn guide bars substantially as follows:

TABLE II

Guide Bar No.	Single pattern				Interchanging patterns									Single pattern			
	1	2	3	4	6A	6B	7A	7B	8A	8B	9A	9B	11	12	13	14	
Needlebed:																	
F-----	2/0	6/4	4/2	2/0	0/2	0/2	4/6	4/6	2/2	2/2	4/4	4/4	2/2	2/2	2/2	4/4	2/2
B-----	2/2	4/4	2/2	2/2	2/2	2/2	4/4	4/4	0/2	0/2	4/6	4/6	4/2	2/0	2/0	6/4	2/4
F-----	2/4	2/4	0/2	2/4	4/2	2/4	4/2	4/2	2/2	2/2	4/4	4/4	2/2	2/2	2/2	4/4	2/4
B-----	4/4	2/2	2/2	4/4	2/2	4/4	2/2	2/2	4/2	4/2	4/2	4/2	0/2	2/4	2/4	2/4	2/4
F-----	6/4	2/0	2/2	4/4	2/2	4/6	2/2	0/2	2/4	4/4	2/4	2/2	2/0	4/2	4/4	2/2	2/2
B-----	4/4	2/2	2/0	4/2	2/4	4/4	2/4	2/2	4/4	4/6	4/4	0/2	0/0	2/2	6/4	2/0	2/0
F-----	2/4	2/4	0/2	2/4	4/2	4/2	4/2	4/2	4/4	4/4	4/4	4/4	2/2	2/2	4/4	2/2	2/2
B-----	2/2	4/4	2/2	2/2	2/2	2/2	4/4	4/4	4/2	4/2	4/2	4/2	0/2	2/4	2/4	2/4	2/4

wherein F denotes front needlebed and B denotes back needlebed; wherein the basic yarn guide bars are denoted by 1, 2, 13, and 14, outer connector yarn guide bars are denoted by 3, 4, 11, and 12, and intermediate yarn guide bars are denoted by 6, 7, 8, and 9; and wherein side-by-side partial-width tubes are produced when the intermediate yarn guide bars follow the A pattern, and unitary full-width tubing is produced when the same bars follow the B pattern.

4. Warp-knitting according to claim 3, utilizing starting points substantially as follows:

TABLE I

Chain Drum	Guide Bar	Pattern Link	Between Needles
Right	<u>1</u>	2/0	1,2
Right	<u>2</u>	6/4	3,4
Right	<u>3</u>	4/2	2,3
Right	<u>4</u>	2/0	2w-1,2w
	<u>5</u>	bar out	
Left	<u>6</u>	0/2	w+2,w+3
Left	<u>7</u>	4/6	w-1,w
Left	<u>8</u>	2/2	w+1,w+2
Left	<u>9</u>	4/4	w-1,w
	<u>10</u>	bar out	
Right	<u>11</u>	2/2	1,2
Right	<u>12</u>	2/2	2w-1,2w
Right	<u>13</u>	2/2	1,2
Right	<u>14</u>	4/4	2,3

wherein the band width is $2w$ needles.

5. Process of Raschel knitting alternately bifurcated and unitary seamless tubular fabric having a filigree-like net construction, comprising utilizing a plurality of partially threaded

rows of yarn guides knitting a panel of fabric on a front needlebed, utilizing a plurality of partially threaded rows of yarn guides knitting a panel of fabric on a back needlebed, each such row of yarn guides being threaded x-in, y-out, z-in,

- 5 y-out, where each of x, y, and z (respectively, four, one, and two) is greater than zero but small with respect to the total number of needles in the band width, with the unthreaded yarn guides in the rows for each bed being out of phase with one another; utilizing for each side edge of the fabric on the 10 respective beds yarn guides threaded only at such edge location and knitting principally on one bed only but crossing over during each pattern repetition to knit at least one stitch on the other bed and thereby seamlessly interconnecting the panels of fabric on the respective beds into side-by-side tubes of 15 fabric and upon conversion from bifurcated to unitary construction employing intermediate yarn guides so utilized for connecting the front and back panels at the respective adjacent edges of the bifurcated portions during knitting thereof to knit a corresponding number of stitches at corresponding 20 repetition intervals on adjacent needles located in the same bed but used in formation of the opposite bifurcated portion during knitting thereof, and thereby forming a unitary portion of seamless tubular fabric joined seamlessly to the bifurcated portions; the patterning being such that each guide stitches alternate 25 courses on a given needle and stitches intervening courses on adjacent needles, alternate intervening courses being stitched respectively first on a needle immediately adjacent on one side of the given needle and in the same bed and second on another needle immediately adjacent the given needle, on the opposite side and in the same bed except in the opposite bed for the intermediate guides during formation of the 30 bifurcated portions only.
